AWNNG

Thomas Walters Bradley, Tampa, Fla.

Application July 26, 1945, Serial No. 607,204

3 Claims. (Cl. 20—57.5)

1

This invention relates to metallic awnings and has for its primary purpose the provision of a simple, durable, inexpensive, and efficient structure having a plurality of sections capable of easy assembly and mounting by a single unskilled workman.

Metallic awnings are usually so heavy that they cannot well be lifted and held by a single person while being secured in place. When made at a factory as a single unit, their original cost in addition to the labor required for their delivery and installation is likely to make them prohibitively expensive. When they are not prefabricated, the workmen who install them usually require sheet metal workers' tools for cutting, bending, soldering, and otherwise assembling the parts.

These considerations will prevent the average householder from attempting to construct and install a metal awning in spite of its advantages over ownings of canvas or of wood.

In the present invention, a supporting framework is made in easily handled, relatively small sections which can be secured in place by screws, and upon this support, top and end sections may be set, one at a time, and held firmly in place by screws and twisted wire. All the sections are sufficiently light in weight to be lifted, held in position, and mounted by a single workman using only the tools necessary to drive a screw.

A preferred embodiment of the invention is shown for purposes of illustration in the accompanying drawings, in which Figure 1 is a front elevation of an awning in place over a window; Fig. 2 is a front elevation of one side frame and a bracket; Fig. 3 is a side elevation of the same frame; Fig. 4 is a longitudinal section through a louvered panel on the plane IV—IV of Fig. 1; Figs. 5 to 9, inclusive, are sections taken transversely of the louvered panel on the planes indicated by the lines V—V, VI—VI, VII—VII, VIII—VIII, and IX—IX, of Fig. 4; Fig. 10 is a transverse section of a cap panel on the plane X—X of Fig. 1; Fig. 11 is a fragmentary longitudinal section through the end of a rod in a socket, showing two means for holding them connected; and Fig. 12 is a fragmentary section showing a means for connecting the adjacent edges of a cap panel and a lower panel.

In Fig. 1, an awning is shown as mounted over the upper portion of a window of which the lower sash is seen at 1. The awning preferably consists of an odd number of panels, three of the louvered panels 2 being shown as alternating between four cap panels 3. Each panel is secured

2

at its upper end to a metal wall bracket set in alignment with the other brackets on the wall or frame above the window.

The left end wall bracket 4 seen in front elevation in Fig. 2 and in side elevation in Fig. 3, is provided with sockets 5 and 6 for rod-like members 7 and 8 of an end frame and it will be understood that the right end wall bracket 9 of which only the top is seen in Fig. 1, will be similar to the bracket 4 but having parts reversed. The intermediate wall brackets 10 for the panels 2 and the brackets 11 for the panels 3 are like the bracket 4 without the sockets, which are not needed. Beneath the bracket 4 is a lower bracket 12 with a socket 13 for the lower end of the member 7 and a socket 14 for the inner end of a horizontal brace member 15. An outer corner bracket 16 has socket 17 for the lower end of member 8, socket 18 for the outer end of member 15, and a lateral socket 19 for a cross rod or pipe 20 connecting the end frame formed by the members 7, 8, and 15 with a similar frame at the right end indicated by broken lines in Fig. 1 at 21.

With the wall brackets 4, 9, 10 and 11 secured in place as by screws, the left end panel 22, indicated in Fig. 3 with parts broken away, may be attached to the adjacent end frame 7, 8, and 15 as by wires 23 welded to the face of the panel and twisted around the frame members.

30 A cap panel 3 is shown in section in Fig. 10 as a curved strip of sheet metal having each side edge formed with a flange 24 to cooperate with a similar flange 25 on an adjacent end panel 22 or a louvered panel 2. As shown best in Fig. 12, the ends of the flanges 24 and 25 are doubled on themselves to provide a thickened edge to be engaged within a tube 26 slid along lengthwise of the flanges, the slit in the tube being close enough to engage the thickened edges to prevent them from slipping out of the tube.

In Fig. 4, a panel 2 is shown as having a tapering vertical flange 27, having a plurality of longitudinal slits stamped out to form louvers 28 open for the escape of heated air from the space beneath the awning while keeping out rain.

As seen in Fig. 3 in broken lines above the bracket 4, the upper end of the panel 3 rests upon an inclined flange 29 of the bracket 4 to which it is secured by screws 30 engaging nuts 31 welded to the flange, or by other suitable fastening means.

In Fig. 4, the top end of the panel 2 rests upon the lower flange 32 of the bracket 10, to which it is held by screws 33. While the section in

Fig. 9 shows all the panels in the same general level of their center lines at their lower ends, the upper ends (in Fig. 5) are at a difference of level determined by the space between the flanges 29 and 32 and the curved bottom central portions of the panels 2 form sloping drainage channels between the more greatly inclined cap panels 3.

The assembly of alternating cap and channel panels on the brackets and supporting frames with one cap panel at one end and another cap panel at the other end, will give a symmetrical appearance to the awning. By providing panels of different standard widths, a set may be selected to suit various widths of windows and frames and give the proper spread.

As a means for securing the members 7, 8, 15, and 19 in their sockets, Fig. 11 shows the socket 18 as having recesses formed by boring holes 34 through the walls of the socket and then providing the outer end of the holes with a screw 35 or a welded plug 36, and the member 15 formed as a tube with a solid end piece 37 welded in the end of the tube and having bored holes 38 for sliding detents 39, thrust outward by spring 40 or elastic material 41, into the holes 34. With the detents pressed back into the holes 38, the end piece 37 can be slid into the socket until the detents are pushed out into the recesses to lock the member in place. The screw 35 is for easy removal of the detent if desired, while the welding 36 gives a much more difficult fastening to release.

Many variations in details of construction, size, and proportion of parts may be made without departure from the invention as claimed.

I claim:

1. An awning comprising a plurality of inclined panels, each panel having means at its upper end for attaching it to a wall, the panels being arranged in two series, an upper series of cap panels and a lower series of panels each having tapering flanges extending vertically along opposite edges to form sloping drainage channels diminishing in depth outwardly from the wall, and means for securing the upper edge of each tapering flange to the adjacent edge of a cap panel.
2. A structure as in claim 1 in which the vertical flanges have louvers formed therein for the escape of air from beneath the panels.
3. An awning including a panel having each side formed with a vertical tapering flange having a laterally extending upper edge portion, and a cap panel adjacent to each flange and having an edge portion engaging the edge portion of the flange, and means for securing the engaging edge portions together.

THOMAS WALTERS BRADLEY.
